UNITED STATES PATENT OFFICE.

FRED J. SEVERIN, OF IMPERIAL, CALIFORNIA.

CAPPING-MELTER.

1,179,228.

Specification of Letters Patent. Patented Apr. 11, 1916.

Application filed June 16, 1915. Serial No. 34,442.

To all whom it may concern:

Be it known that I, FRED J. SEVERIN, a citizen of the United States of America, residing at Imperial, in the county of Imperial and State of California, have invented certain new and useful Improvements in Capping-Melters; and I do hereby declare the following to be a full, clear, and exact description of the invention, such as will enable others skilled in the art to which it appertains to make and use the same.

This invention is an improved capping melter for use in melting the cappings and other like material from honeycombs, the object of the invention being to provide an improved device of this character which is cheap and simple, is very strong and durable, which requires only one burner of a gasolene or other stove and which is thoroughly efficient in operation.

The invention consists in the construction, combination and arrangement of devices hereinafter described and claimed.

In the accompanying drawings:—Figure 1 is partly an elevation and partly a longitudinal sectional view of a capping melter constructed in accordance with my invention. Fig. 2 is a plan of the same. Fig. 3 is a detail sectional view of the false bottom or partition plate and one of the tubes.

In accordance with my invention the body 1 of the melter, which is here shown as of oblong rectangular form, but which may be of any suitable shape and of any suitable size, has its walls formed with outwardly and upwardly flared upper portions 2. An upper partition plate or false bottom 3 is arranged horizontally in the body at the point where the flares 2 merge with the vertical walls and in practice this false bottom or upper partition plate is made preferably of heavy tinned copper. A lower partition plate 4, which is also preferably made of tinned copper is spaced a suitable distance below the plate 3 and is connected thereto by tubes 5 the ends of which are secured in openings 4' with which the plates 3—4 are provided said openings being circular and said tubes being cylindrical. In practice in a melter in which the plate 3 is 17x13 inches, the tubes are one half inch in diameter and 221 of said tubes are provided.

A collection pan 6 is arranged a suitable distance below the lower partition plate 4

and is provided at the outer end of the melter with a honey spout 7. The bottom 8 of the melter is spaced a suitable distance below the collection pan, to form a waterway or chamber 9 which is both below and above the collection pan and includes the space between the plates 3—4 and also includes the space 10 which is formed between one of the end walls 11 of the body 1 and a contiguous inclined wall 12 which rises from the bottom or partition plate 3. That portion of the waterway between the walls 11—12 is adapted for the reception of one or more uncapping knives 14 and also serves as an inlet to enable water to be supplied to the waterways.

The body may be made of iron or other suitable material and in practice is preferably rustproof. Teuton iron is a suitable material for the body of the melter.

It will be noted that the collection pan is arranged between the top and bottom of the waterway so that it is subjected to the action of heat from the hot water, both above and below and it will be also observed that the tubes which connect the false bottom 3 with the collection pan are arranged in the hot water in the waterway. A screw cap 16 is provided for the purpose of discharging water out of the melter when desired without the necessity of tipping up the melter.

In the operation of the melter the same is placed on a gasolene or other stove over a lighted burner and with a sufficient quantity of water in the chamber 9 to entirely fill the same and to also nearly fill the space 10. The water is heated to the requisite degree. The cappings to be melted are placed in the receiver 17 formed by the perforated plate 3 and the flares 2 of the walls, and are melted by the heat, the melted material running down through the tubes 5 into the collection pan 6 and passing off through the spout 7.

If necessary the cappings and other material may be worked by a paddle while being melted.

The shape of the tubes 5, which is cylindrical, greatly facilitates the passage of the melted material therethrough, and said tubes owing to their heated surfaces cause all of the material to be thoroughly melted.

Having thus described my invention, I claim:—

1. A capping melter of the class described

- comprising a body having a bottom and side and end walls, a collection pan spaced from the bottom and having a spout leading through out one wall of the body, an upper 5 false bottom or partition spaced above the collection pan and arranged between the walls, a lower partition spaced below the upper partition and forming the top of the honey pan, so that a water way is formed 10 above and below the collection pan, and tubes connecting the upper false bottom and lower false bottom or partition and extending therethrough and communicating at their lower ends with said collection pan said 15 tubes being arranged in that portion of the waterway above the collection pan.
2. A capping melter of the class described comprising a body having a bottom and side and end walls, a collection pan spaced from the bottom and having a spout leading through out one wall of the body, an upper 20 false bottom or partition spaced above the collection pan and arranged between the walls, a lower partition spaced below the upper partition and forming the top of the collection pan so that a waterway is formed 25 above and below the honey pan, and tubes connecting the upper false bottom and lower false bottom or partition and extending therethrough and communicating at their lower ends with said collection pan said tubes being arranged in that portion of the 30 waterway above the honey pan, and said tubes being cylindrical in form, and a wall spaced from one end of the end walls and coacting with it to form an inclined intake portion of the waterway, open at its upper 35 side, and adapted also for the reception of the uncapping knives.

of the waterway above the collection pan, and said tubes being cylindrical in form.

3. A capping melter of the class described comprising a body having a bottom and side and end walls, a collection pan spaced from the bottom and having a spout leading through out one wall of the body, an upper 40 false bottom or partition spaced above the collection pan and arranged between the walls, a lower partition spaced below the upper partition and forming the top of the collection pan so that a waterway is formed 45 above and below the honey pan, and tubes connecting the upper false bottom and lower false bottom or partition and extending therethrough and communicating at their lower ends with said collection pan said tubes being arranged in that portion of the 50 waterway above the honey pan, and said tubes being cylindrical in form, and a wall spaced from one end of the end walls and coacting with it to form an inclined intake 55 portion of the waterway, open at its upper side, and adapted also for the reception of the uncapping knives.

In testimony whereof I affix my signature in presence of two witnesses.

FRED J. SEVERIN.
